UNITED STATES PATENT OFFICE.

CLAUD E. HARLAN, OF WATSONVILLE, CALIFORNIA.

SPARK-PLUG TESTER.

1,249,953.

Specification of Letters Patent. Patented Dec. 11, 1917.

Application filed February 19, 1916. Serial No. 79,324.

To all whom it may concern:

Be it known that I, CLAUD E. HARLAN, a citizen of the United States, residing at Watsonville, in the county of Santa Cruz and State of California, have invented new and useful Improvements in Spark-Plug Testers, of which the following is a specification.

This invention relates to a spark plug 10 tester and particularly to improvements on my former patent entitled "Sparking indicator," issued December 28, 1915, No. 1,166,366.

One of the objects of the present invention 15 is to provide a simple, portable testing instrument for locating trouble in the ignition system of internal combustion engines, for instance, to determine whether the trouble is caused by a fouled plug, a short circuit in 20 the wiring connections, punctured insulation, magneto trouble, etc. Another object of the present invention is to provide means for testing the resistance to the passage of the current through the several plugs and connected wiring. Further objects will herein- 25 after appear.

The invention consists of the parts and the construction and combination of parts as 30 hereinabove more fully described and claimed, having reference to the accompanying drawings, in which—

Figure 1 is a diagrammatic view illustrating the testing instrument and its connections.

Fig. 2 is a cross section on the line 2—2 of Fig. 1.

Referring to the drawings in detail, A indicates a frame which is adapted to be secured directly on the engine by means of a 40 pair of bracket extensions 2. Rigidly secured centrally of the frame is a cross-bar 3, preferably constructed of an insulating material, such as fiber, porcelain, or the like, and secured in said cross-bar is a plurality of 45 sparking points 4.

Below the stationary cross-bar 3, turnably mounted in the frame, is a roller 5. This is also preferably constructed of an insulating material and has secured thereon a plurality 50 of sparking points 6 mounted in direct alignment with the sparking points 4 on the stationary bar. The roller 5 is preferably mounted on a shaft extending through the frame and is provided with a handle 7, on 55 the end, to permit the shaft and roller to be turned, and a set-screw 8 for locking the

roller in adjusted position. Turnably mounted in the frame, above the stationary cross-bar, in a manner similar to the lower roller 5, is a roller 9, also constructed of insulating material and provided with a handle 10 and a set-screw 11 to lock it against turning movement.

Suitably secured on the roller 9 is a metal plate, extending the entire length of the 60 roller and having its ends contacting with the frame to form a ground circuit therewith, as will hereinafter be described. This bar will hereinafter be termed the resistance bar 12.

In operation, when it is desired to locate any trouble in the ignition circuit, it is accomplished by securing the frame A at any convenient point, but preferably upon the engine cylinders indicated at B. This forms 70 a ground circuit for the frame and also the resistance bar 12. The secondary wires of the magneto usually, connected with the spark plugs 14, are now connected with the terminals 15 of the sparking points 4, as 80 shown in Fig. 2, and the terminals 16 of the sparking points 6 are connected by wires 17 with their individual spark plugs; the ground of the magneto being connected by means of a wire 18 with any suitable contact on the engine in the usual manner. The engine can now be started and is preferably 85 made to run at a comparatively slow speed while certain tests are being conducted.

The electric current generated by the magneto, in order to complete its circuit through the engine plugs, will have to jump the gap formed between the sparking points 4 and 6. The current flow can thus be observed at this point. The distance between the sparking 95 points is gradually increased as the test is progressing by turning the roller 5, by means of the handle 7, until the gap produced approximates a half inch or more. If the current continues to jump between the several 100 sparking points, after a half inch gap has been secured, it will immediately indicate that the magneto, with connected wiring and spark plugs, is in good condition and proper working order and that engine troubles, if any, will have to be looked for in some other place.

If the spark becomes extinguished between any one set of sparking points 4 and 6, when a half inch gap has been secured 110 or previous thereto, it will immediately indicate that something is wrong in this cir-

cuit. For instance, leakage may occur in the wiring or connections or the contact points in the distributor of the magneto may be set too far apart or may be partly corroded, or a short circuit in the connections may be found. The testing instrument will in all cases indicate the defective circuit, making it comparatively easy to locate the actual defect. It can, therefore, be seen that if any connections between the engine plugs and magneto are short-circuited or otherwise defective, as the distance between the sparking points increases, the resistance to the passage of current will become so great that the spark in the defective circuit will immediately become extinguished, as the current in the defective circuit will not be strong enough to jump the gap between the sparking plugs.

One of the important features of the present invention is the provision of the resistance bar 12. This is employed for the purpose of testing the resistance to the passage of current through the spark plugs, with connected wiring, and is accomplished by turning the roller 9 until the bar 12 assumes the full line position shown in Fig. 1.

With the engine running at slow speed a low compression is created in the engine cylinders and resistance to the current jumping the gaps in the plugs is comparatively small. In this instance it is possible to move the bar to a point approximately $\frac{1}{8}$ of an inch away from the sparking points 4 before the spark will leave the gap in the plug terminals and jump across to the bar which is grounded with relation to the magneto. It has been found that for some unknown reason some spark plugs are naturally highly resistant to the flow of a current. This resistance is again often increased by corrosion on the sparking points or a slight coating of carbon on the same. A plug thus effected causes considerable trouble in an engine as it will permit the spark to jump the points of the plug when the engine is running under a small load and low compression and will, therefore, to all appearances, be in perfect working order. This plug, however, will be so resistant to the flow of the current that the moment the load or compression of the engine is increased no spark can pass the gap. The spark will then jump across to the grounding bar and in some instances jumps the space of a half inch or more, immediately indicating that the connected plug is either corroded, coated with a carbon or otherwise resistant to the passage of the current. This defect can sometimes be overcome by cleaning or filing the sparking points of the plug or bringing the points closer together in this manner decreasing the resistance through the plug by removing the cause of the trouble.

In actual practice where all the plugs are in perfect condition, it is found that $\frac{1}{2}$ of an inch spacing between the resistance bar and the points 4 must be reached before the spark will leave the plug points and jump across to the bar, but any defective plug, or one that is resistant to the current, will begin to jump across the bar long before a $\frac{1}{2}$ of an inch spacing is secured, thus indicating immediately which plug is defective.

The construction of the testing instrument here shown permits the ignition system of any internal combustion engine to be tested while the engine is running, and also eliminates the necessity of removing the engine plugs while the test is being made. The test, although preferably made at low speed as the spark can then be most easily observed, can be made at various engine speeds; this being an important feature of the present invention as the current output of some generators or magnetos varies greatly with the change in speed.

While the specifications describe the current jumping a one-half inch gap under favorable conditions, I wish it understood that this distance is not fixed, as one make of magneto may jump a larger gap under the same conditions while another make may only jump a three-eighths or one-quarter inch gap.

The materials and finish of the several parts of the testing instrument are such as the experience and judgment of the manufacturer may dictate.

I wish it understood that various changes in form, proportions and minor details of construction may be resorted to within the scope of the appended claims and that I do not wish to limit myself to the specific design and construction here shown.

Having thus described my invention, what I claim and desire to secure by Letters Patent is—

1. The combination with a grounded frame and a plurality of spark gap members carried by and insulated from the frame, of a resistance testing bar grounded to the frame and adjustable to and from the spark gap members.
2. A spark plug tester comprising a frame, a stationary bar secured on and insulated from the frame, a plurality of sparking points secured on said bar and insulated from each other, a movable bar mounted on and insulated from the frame, a plurality of sparking points secured on said bar and insulated from each other, means for connecting one set of sparking points with the secondary wires on a magneto and the other set of sparking points with the spark plugs on an internal combustion engine, and a movable resistance testing bar grounded to the frame and adjustable to and from one set of sparking points.

3. The combination with an internal combustion engine, of a spark plug tester comprising a frame adapted to be grounded to the engine, a stationary roller secured in and insulated from the frame, a plurality of 5 sparking points secured on said roller and insulated from each other, a turnable roller mounted in the frame and insulated therefrom, a plurality of sparking points 10 secured on said roller and insulated from each other, a second roller turnably mounted in the frame and grounded thereto, and a resistance bar carried by said roller adapted to be moved into and out of engagement 15 with the sparking points on the stationary roller when the roller upon which it is mounted is turned.

4. The combination with an internal combustion engine, of a spark plug tester comprising a frame adapted to be grounded to the engine, a stationary roller secured in and insulated from the frame, a plurality 20 of sparking points secured on said roller and insulated from each other, a turnable roller mounted in the frame and insulated therefrom, a plurality of sparking points secured on said roller and insulated from each other, a second roller turnably mounted in the frame and grounded thereto, a resistance bar carried by said roller adapted to be moved into and out of engagement 25 with the sparking points on the stationary roller when the roller upon which it is mounted is turned, means for locking the 30 first named turnable roller against movement, and means for locking the second named turnable roller against movement.

5. A device of the character described comprising a frame, a plurality of double 35 contact members carried by said frame and connected with one side of a source of electrical energy, a resistance testing member connected with the other side of said source

and movable to and from the upper sides of said double contact members, and a plurality 45 of single contact members movable into electrical connection with the lower sides of said double contact members.

6. A sparking indicator comprising, in combination, a stationary holder, a movable 50 holder adjustably mounted on same, a plurality of sparking points secured on the stationary holder and insulated from same, a plurality of sparking points secured on the movable holder and insulated from same, 55 means for connecting the sparking points on the movable holder with the secondary wires of a magneto, means for connecting the sparking points on the stationary holder with the spark plugs on an internal combustion 60 engine, and a grounding bar adjustably mounted with relation to the sparking points on the movable holder, said grounding bar being grounded with relation to the magneto.

7. A device of the character described comprising a frame, a plurality of double contact members carried by said frame and connected with one side of a source of electrical energy, a resistance testing member 70 connected with the other side of said source and movable to and from the upper sides of said double contact members, a plurality of single contact members movable into electrical connection with the lower sides 75 of said double contact members, and means for locking said double contact members and said resistance testing member in adjusted position.

In testimony whereof I have hereunto set 80 my hand in the presence of two subscribing witnesses.

CLAUD E. HARLAN.
